UNITED STATES PATENT OFFICE.

WILLIAM H. WILDER, DECEASED, LATE OF GARDNER, MASSACHUSETTS, BY SOLON WILDER, ADMINISTRATOR, OF GARDNER, MASSACHUSETTS, AND FRED E. WHITE, OF GARDNER, MASSACHUSETTS.

OVEN.

1,161,365.

Specification of Letters Patent.

Patented Nov. 23, 1915.

Original application filed February 7, 1912, Serial No. 676,100. Divided and this application filed April 29, 1915. Serial No. 24,762.

To all whom it may concern:

Be it known that WILLIAM H. WILDER, late a citizen of the United States, residing at Gardner, Massachusetts, and now deceased, and I, FRED E. WHITE, a citizen of the United States, residing at Gardner, Massachusetts, did invent certain new and useful Improvements in Ovens, of which the following is a specification.

10 The present invention relates to an improved fastening device intended more especially for use on the doors of ovens of the character used in connection with gas or vapor stoves. In such ovens, in order to have 15 the door held tightly closed it is necessary to have fastening devices at the corners as such doors are usually made of light sheet metal which has some tendency to warp under the heat. Such corner fastenings as 20 have heretofore been employed, so far as we are aware require the use of both hands of 25 the operator to manipulate them which is exceedingly inconvenient as it is frequently desired to open the oven door with one hand while holding a dish with the other hand.

The object of the present invention is to 30 provide a simple and efficient form of fastening device which will hold the door tightly at the corners and which may yet be manipulated by one hand serving both to 35 unfasten the holding devices and as a means for lowering and raising the door which is usually hinged at the bottom and which when open serves as a shelf.

35 The invention includes the novel features of construction defined in the appended claim and hereinafter more particularly described in connection with the accompanying drawings, in which,

40 Figure 1 is a front elevation of an oven and door with the improved fastening device applied thereto, and Fig. 2 is an enlarged sectional detail being a section on line 2-2 of Fig. 1 looking to the right.

45 Referring by reference characters to this drawing, the numeral 1 designates the outer case or shell of the oven, which is preferably of the form disclosed in application No. 676,100 filed Feb. 7, 1912, of which the present case is a division.

50 7 indicates the door of the oven which is hinged at its lower edge preferably by means of arms 8 entering slots 9 in the lower cor-

ners of the front wall of the oven as more clearly disclosed in the application referred to.

The improved locking device comprises a single wire or steel rod 11 journaled in clips 12 which have their ends passed through openings in the door and clenched over upon the inside thereof. The wire or rod has its intermediate portion projected outward and coiled to form an arm and handle as indicated at 11^a, while the ends are extended inward and designed to enter slots 13 in the front wall of the case, being bent back to form hooks as indicated at 11^b, which when the rod is rocked upon its handle not only serve to engage and disengage the edges of the slots but to draw the upper corners of the door and hence the entire upper edge of the door tightly against the front edge or face of the oven.

It is preferred to provide the front wall of the oven adjacent the slots through which the arms pass with inwardly projecting portions 1^c with which the hooks 11^b engage with a stay or cam or friction wall thus preventing disengagement of the parts.

Having described the invention as more particularly adapted for an oven door, it will be understood that it is not desired to restrict it to this use as it is applicable to any form of door which desires to be held at the corners and it will be capable of manipulation by one hand.

Having thus described the invention, what is claimed is:-

In combination with an oven, a door for the same, a fastening device and handle at the upper end of the door, including a rod having its ends extended inwardly through slots in the wall of the oven and terminating in S-shaped hooks engaging inwardly extending portions of the oven wall and adapted to draw the corners of the door tightly against the oven, the parts being adapted to be disengaged to open the door by the lifting of the handle, substantially as described.

Signed at Gardner, Massachusetts, this 14th day of April, 1915.

SOLON WILDER,

Administrator

FRED E. WHITE.
